UNITED STATES PATENT OFFICE.

STEPHEN M. WIRTS, OF DETROIT, MICHIGAN, ASSIGNOR TO AMERICAN GRAPHOPHONE COMPANY, OF BRIDGEPORT, CONNECTICUT, A CORPORATION OF WEST VIRGINIA.

DESIGN FOR A CABINET FOR TALKING-MACHINES.

43,293.

Specification for Design.

Patented Nov. 26, 1912.

Application filed August 30, 1912. Serial No. 717,952. Term of patent 14 years.

To all whom it may concern:

Be it known that I, STEPHEN M. WIRTS, a citizen of the United States, and a resident of Detroit, Michigan, whose post-office address is 84 Hague avenue, Detroit, Michigan, have invented a new, original, and ornamental Design for a Cabinet for Talking-Machines, reference being had to the annexed drawing, forming part hereof, which is a perspective view illustrating my said invention.

I claim:

The ornamental design for cabinet for talking-machines, as shown.

In testimony whereof I have signed this specification in the presence of two subscribing witnesses.

STEPHEN M. WIRTS.

Witnesses:

FLORENCE M. SHERIDAN,
MABEL E. SYMES.
